50 and 51 are of wood and 52 is a wooden
55 rail or bearing rail 18 inches wide. 53 is a
guide rail "feeler" 54 is a slot 55 is a roller and
56 is a spring which holds the slot 54 in the
57 rail 53.

UNITED STATES PATENT OFFICE.

EBBERT ASHBY JONES, OF DANVILLE, VIRGINIA.

SPINNING-MACHINE.

1,206,542.

Specification of Letters Patent. Patented Nov. 28, 1916.

Application filed December 30, 1914. Serial No. 879,770.

To all whom it may concern:

Be it known that I, EBBERT A. JONES, a citizen of the United States, and a resident of Danville, in the county of Pittsylvania and State of Virginia, have made certain new and useful Improvements in Spinning-Machines, of which the following is a specification.

My invention relates to improvements in spinning machines, and it consists in the combinations, constructions and arrangements herein described and claimed.

In the spinning of yarns, the bobbins upon which the yarn is wound have a primary winding which is termed the "bunch". This winding extends for a certain distance upwardly from the bottom of the spindle and is necessary for the purpose of providing an engaging member for a "feeler" which prevents the danger of winding off of all the yarn on the bobbin in a manner well known to the art. This so-called "bunch" represents just so much waste yarn or thread and is a considerable source of loss since with the large number of bobbins the amount of yarn or thread which is consumed in making the "bunch" amounts to a very substantial item of expense.

An object of my invention is to provide a device by means of which the amount of yarn on the "bunch" may be reduced to approximately one-half or even less, thereby economizing in the amount of yarn which would otherwise be available only as waste.

A further object of my invention is to provide a device of the type described which will form a "bunch" of less yarn or thread, because the throw or stroke of the guide rail is reduced by my invention, while at the same time means is provided for permitting a normal stroke or reciprocatory movement of the guide rail when the "bunch" has been formed.

A further object of my invention is to provide a device by means of which the movement of the guide rail may be lessened while forming the bunch, this movement being secured by the provision of an auxiliary cam for controlling the throw or stroke of the guide rail with means for putting said auxiliary cam out of operation and for bringing into operation the main cam which controls the movement of the rail in forming the remainder of the winding on the bobbin.

A further object of my invention is to

provide a device which may be applied to existing spinning machines without the necessity of dismantling the machines in any way or of interfering in the ordinary operation of the machine.

Other objects and advantages will appear in the following specification and the novel features of the invention will be particularly pointed out in the appended claims.

My invention is illustrated in the accompanying drawings forming part of this application in which—

Figure 1 is a plan view of the device as applied to a spinning machine. Fig. 2 is a side view thereof, Fig. 3 is an end view of the device showing its application to a spinning machine. Fig. 4 is a face view showing the relation of the cam and the main cam, Fig. 5 is a sectional view along the line 5—5 of Fig. 2, Fig. 6 is a view of the device looking at the opposite side from that shown in Fig. 2, Fig. 7 is a view somewhat similar to Fig. 2 showing the parts in another position. Fig. 8 is a detail side view of a portion of the device. Fig. 9 is a detail view showing the auxiliary cam in one position, and Fig. 10 is a view similar to Fig. 9, showing the auxiliary cam in another position.

In explaining my invention it is necessary for me to describe and show certain parts of a common type of spinning mechanism in order that the improvement may be readily understood. I will describe, however, only so much of the old structure as is necessary for a thorough understanding of my improvement.

Referring especially to Figs. 3, 6 and 7, I have shown therein a main frame 1 upon which is mounted a stub shaft 2 bearing a builder arm 3 to which is secured a sprocket chain 4 which is attached at 5 to the arm and which passes around an idler 6 on a 100 slideable plate carried by the arm, thence over a pulley or idler 7 and is attached to the segment 8 of a bell-crank lever 9 which is pivoted at 10 to the frame. The segment is provided with a connecting member 11 leading to a bell-crank lever 12 which is pivoted at 13 and whose arm bears on a vertically slideable push rod 14 which is guided in bearings or slots 15 and which bears at its upper end a rail 16 whose reciprocal vertical movement is designed to guide the thread or yarn upon the bobbins such as that shown at 17

in Fig. 3. Secured at the end of the power shaft 18 is a cam 19 which bears on a roller 20 on an adjustable plate 21 carried by the arm 3.

As is well known in this art the winding of the yarn upon the bobbin 17 is accomplished through the aid of the guide rail 16, beginning at the bottom of the bobbin and guiding the thread up and down for a limited portion of the bobbin, this guiding movement being such as to have a progressive motion toward the top of the bobbin. The reciprocating motion of the guide rail is caused by the cam 19, for when the cam 15 engages the wheel 20 it will push downwardly on the arm 3 pulling the sprocket chain 4, thus causing the lowering of the push rod 14 through the medium of the pull rod 28 and the bell-crank lever 12, the cam 20 being shaped as shown to cause the rod to raise and lower. The progressive motion is caused by a ratchet wheel 22 at the end of a shaft 25 which is rotatably carried by the arm 3. This shaft bears a plate 38 which 25 is loosely mounted thereon and which carries a pawl 23 arranged to engage the ratchet wheel 22. A fixed member 24 is disposed in the path of the pawl so as to bring the latter into engagement with the teeth 30 of the ratchet wheel at each upward movement of the arm 3, thus causing the rotation of the ratchet wheel at each upward movement. On the shaft 25 is disposed a worm 26 which engages a slidable rack member 27 that bears an idler 6. It will be seen that as the ratchet is turned the worm 26 causes a movement of the plate 27 so as to slacken up the chain 4 and thus permit the pull rod 28 which operates the bell-crank 40 lever to move the push rod progressively higher. The stroke of the push rod 14, however, will be the same since it depends upon the shape and size of the cam 19.

The parts thus described are old and form 45 no part of my invention except in so far as they coöperate with the parts about to be described.

Referring particularly to Fig. 2 I have shown therein a bell-crank lever which is 50 pivoted on a stub shaft 29 carried by a plate 30 secured to the arm 3 by bolts 31 or in any other suitable manner. One arm 32^a of the bell-crank lever bears a roller 33, the other arm 32^b being connected by means of a link 55 and turnbuckle connection 34 with a link 35 which is mounted on a pivot bolt 36 carried by the arm 3. The position of the bell crank levers 32^a, 32^b, and hence of the cam roller 33, depends upon the position of the stop member 36^a. When the bell crank lever is in 60 its effective position, the stop 36^a bears against the arm 32^b. The stop 36^a is carried by the plate 27 and moves with it as the latter is moved by the worm 26. On the 65 power shaft I mount an auxiliary cam 37

which, as will be seen, is smaller than the cam 19. This cam 37 is arranged to bear on the roller 33 when the "bunch" is being made, the main cam 19 also being in operation during the building of the bunch, but the device is so arranged that the main cam 19 alone comes into play for the further winding of the bobbin, as will be explained later. As stated before the shaft 25 bears a loosely mounted plate 38 which carries a pawl 23 which engages the ratchet wheel 22. A second plate 38^a which bears a stop pin 39 is loosely mounted on the shaft 25 and is provided with an extension 38^a carrying a set screw 38^b (see Fig. 1) which extends through a slot 38^c in an enlarged weighted portion 38^d of the plate 38. This construction forms a means by which the relative position of the pin 39 with respect to the pivotal support of the pawl 23 may be varied. This pin 39 extends underneath the pivotal support 36 of the link 35.

From the foregoing description of the various parts of the device the operation thereof may be readily understood. The purpose of the auxiliary cam 37 is to shorten the stroke of the large cam 19 while the bunch is being made. The cams are placed in the relative positions shown in Fig. 4 so that during the rotation of the shaft 18 which bears the cams, the auxiliary cam 37 will at times engage the cam roller 33 so as to move the arm 3 from the control of the cam 19 and thus cut the stroke in two or shorten the stroke while the bunch is being made, as will be explained later. The normal position of the roller 33 at the beginning of the winding operation is that shown in dotted lines in Fig. 2, or that shown in detail in Fig. 5. The roller 33 is held in this position by the engagement of the arm 32^b of the bell crank lever with the stop pin 36^a which, as stated before, is carried by the plate 27 and which at the beginning of the operation is in the position shown in Fig. 9. It will be understood that the arm 32^b gradually recedes, as explained later, from the position shown in Fig. 9, which finally allows the high parts of the cam 19 to come into contact with the coating roller 20 and actuate the builder arm jointly with the action of the cam 37 on the roller 33. The rotation of the auxiliary cam 37 will cause the reciprocatory rocking of the arm and this will cause the guide rail to move up and down so as to wind the "bunch" onto the bobbin. During the upward movement of the arm 3 the pawl 23 will strike the fixed member 24 and will thus cause the turning of the ratchet wheel. As the ratchet is turned the shaft 25 which is secured to it will be rotated and the movement of the screw 26 will cause a movement of the plate 27 so as to move the stop pin 36^a from the position shown in Fig. 9 toward that shown in Fig. 10. This will permit the

bell crank lever to move from the position shown in Fig. 9 toward that shown in Fig. 10. It will be understood that this movement is very slight for each up and down movement of the arm. On the upward movement of the arm, the plates 38 and 38', the pawl 23 which is carried by the former, and the pin 39 which is carried by the latter, will resume their original positions because of the fact that the end 38^a of the plate 38 together with the extension of the plate 38', overbalance the pawl and pin end of these plates, thereby causing them to ascend until the pin 39 strikes the arm 3. In the next forward movement, the pawl 23 will again strike the fixed member 24 and the shaft 25 will be rotated a little farther, the pin 36^a will be moved and the bell crank lever will follow it. It will be observed that the link 35 which is connected to the bell crank lever by the turn buckle connection is gradually assuming a vertical position during the progressive movement of the pin 36^a. The link 35 finally gets in the path of the pin 39 so that the latter on its return by the weighted end of the plate does not reach its normal position, but is now stopped by the lower end of the link 35. This prevents the pawl 23 from riding over as many teeth as it would at the beginning of the operation, and hence shortens the angle through which the ratchet wheel is rotated. The auxiliary cam 37 is now out of commission because the cam roller 33 has been lowered past the point of engagement with the cam 37. This allows the large cam 19 to have full control of the stroke of the arm 3. Since the large cam is greater in dimension, the throw or stroke of the arm 3 will now be a maximum, that is to say, the stroke will now conform to the requirement for winding the thread on the bobbin, the bunch having been made. While the cams 19 and 37 are working conjointly to cause the reciprocation of the arm during the making of the bunch, a short stroke is produced, but when the cam 19 takes full control a long stroke is produced. Now it is essential that the rotation of the shaft 25 which is caused as stated by the engagement of the pawl 23 with the fixed member 24, shall be substantially the same during each stroke, whether the stroke be short or long for the reason that the building of the thread on the bobbin must be uniform. It will therefore be seen that when the link 35 comes into engagement with the pin 39 it will stop the return movement of the pawl at such a point that subsequent long strokes will move the pawl substantially through the same arc as it is moved by the short stroke when the link 35 is out of the way of the pin 39, so as to permit it to have a return movement until the pin engages the arm 3. This feature I regard as one of the most important features of my invention, be-

cause it is the automatic regulation of the number of "pick" taken during each reciprocatory movement.

It will be observed therefore that the invention lies not merely in providing an auxiliary cam to control the stroke of the arm at the beginning of the formation of the bunch, but to control the number of picks taken while the bunch is being formed and to automatically continue such control while the main portion of the bobbin is being wound subsequent to the formation of the bunch. In the position of the link 35 shown in Fig. 8, the pivotal point of the link 35 and its pivotal connection to the link and turnbuckle 35^x will be dead centred with respect to the pin 39, thus locking the "bunch" control mechanism out of operative engagement so that there is no possibility of the operation of these parts after their function has been concluded. When the bobbins have been wound the auxiliary control mechanism, *i. e.*, the parts 32^a, 32^b, 33, 34 and 35 are placed in their original position and the shaft 25 is rotated back to its original position by means of the handle 40 in the ordinary manner the pawl 23 being held out of engagement with the ratchet 22, and the operation can be repeated.

I claim:

1. In a spinning machine, a power shaft, a main cam carried by said power shaft, an auxiliary cam carried by said power shaft, a builder arm, a bell crank lever, a roller carried by said bell crank lever and arranged to be engaged by said auxiliary cam, a roller carried by said builder arm and arranged to be engaged by said main cam, a shiftable stop member arranged to engage said bell crank lever for controlling the position of the roller with respect to the auxiliary cam, and means operated by the movement of said builder arm for moving the shiftable stop member, said last named means comprising a slidable plate carried by the arm, and means operated through the reciprocatory movement of the arm for causing a progressive movement of the plate.

2. In a spinning machine, a power shaft, a main cam carried by said power shaft, an auxiliary cam carried by said power shaft, a builder arm, a bell crank lever, a roller carried by said bell crank lever and arranged to be engaged by said auxiliary cam, a roller carried by said builder arm and arranged to be engaged by said main cam, a shiftable stop member arranged to engage said bell crank lever for controlling the position of the roller with respect to the auxiliary cam, and means operated by the movement of said builder arm for moving the shiftable stop member, said means comprising a slidable plate carried by the builder arm arranged to bear the shiftable stop, a rack carried by the plate, a shaft rotatably

- carried by the arm and bearing a worm arranged to engage the rack, and means for rotating said last named shaft.
3. In a spinning machine, a power shaft, a main cam carried by said power shaft, an auxiliary cam carried by said power shaft, a builder arm, a bell crank lever, a roller carried by said bell crank lever and arranged to be engaged by said auxiliary cam, a roller carried by said builder arm and arranged to be engaged by said main cam, a shiftable stop member arranged to engage said bell crank lever for controlling the position of the roller with respect to the auxiliary cam, and means operated by the movement of said builder arm for moving the shiftable stop member, said means comprising a slideable plate carried by the builder arm arranged to bear the shiftable stop, a rack carried by the plate, a shaft rotatably carried by the arm and bearing a worm arranged to engage the rack, a ratchet carried by said last named shaft, a weighted pawl pivotally mounted on said builder arm and arranged to engage said ratchet, a fixed stop member arranged to engage the pawl, and means for automatically controlling the movement of the pivoted weighted pawl.
- 10 5. In a spinning machine, a power shaft, a main cam carried by said power shaft, an auxiliary cam carried by said power shaft, a builder arm, a bell crank lever, a roller carried by said bell crank lever and arranged to be engaged by said auxiliary cam, a roller carried by said builder arm and arranged to be engaged by said bell crank lever for controlling the position of the roller with respect to the auxiliary cam, means operated by the movement of said builder arm for moving the shiftable stop member, said means comprising a slideable plate carried by the builder arm arranged to bear the shiftable stop, a rack carried by the plate, a shaft rotatably carried by the arm and bearing a worm arranged to engage the rack, a ratchet carried by said last named shaft, a weighted pawl pivotally mounted on said builder arm and arranged to engage said ratchet, and a fixed stop member arranged to engage the pawl.
- 15 4. In a spinning machine, a power shaft, a main cam carried by said power shaft, an auxiliary cam carried by said power shaft, a builder arm, a bell crank lever, a roller carried by said bell crank lever and arranged to be engaged by said auxiliary cam, a roller carried by said builder arm and arranged to be engaged by said bell crank lever for controlling the position of the roller with respect to the auxiliary cam, and means operated by the movement of said builder arm for moving the shiftable stop member, said means comprising a slideable plate carried by the builder arm arranged to bear the shiftable stop, a rack carried by the
- 20 35 40

plate, a shaft rotatably carried by the arm and bearing a worm arranged to engage the rack, a ratchet carried by said last named shaft, a weighted pawl pivotally mounted on said builder arm and arranged to engage said ratchet, a fixed stop member arranged to engage the pawl, and means for automatically controlling the movement of the pivoted weighted pawl.

5. In a spinning machine, a power shaft, a main cam carried by said power shaft, an auxiliary cam carried by said power shaft, a builder arm, a bell crank lever, a roller carried by said bell crank lever and arranged to be engaged by said auxiliary cam, a roller carried by said builder arm and arranged to be engaged by said bell crank lever for controlling the position of the roller with respect to the auxiliary cam, means operated by the movement of said builder arm for moving the shiftable stop member, said means comprising a slideable plate carried by the builder arm arranged to bear the shiftable stop, a rack carried by the plate, a shaft rotatably carried by the arm and bearing a worm arranged to engage the rack, a ratchet carried by said last named shaft, a weighted pawl pivotally mounted on said builder arm and arranged to engage said ratchet, a fixed stop member arranged to engage the pawl, and means for automatically controlling the movement of the pivoted weighted pawl, said last named means comprising a pivoted arm arranged to swing in the path of the pawl, and a link connecting said pivoted arm with said bell crank lever.

EBBERT ASHBY JONES.
